UNITED STATES PATENT OFFICE.

WILLIAM ELIOT BARROWS, OF PHILADELPHIA, PENNSYLVANIA, AS-
SIGNOR TO THE WELSBACH LIGHT COMPANY, OF GLOUCESTER
CITY, NEW JERSEY.

DESIGN FOR A GALLERY FOR INCANDESCENT GAS-LIGHTS.

SPECIFICATION forming part of Design No. 25,780, dated July 14, 1896.

Application filed May 26, 1896. Serial No. 593,188. Term of patent 14 years.

To all whom it may concern:

Be it known that I, WILLIAM ELIOT BARROWS, a citizen of the United States, residing at the city of Philadelphia, in the county 5 of Philadelphia and State of Pennsylvania, have invented and produced a new and original Design for a Gallery for Incandescent Gas-Lights, of which the following, taken in connection with the accompanying drawings, 10 is a specification.

Figure 1 is a top view of a gallery for an incandescent gas-light, showing my design; and Fig. 2 is an elevational view of the same, also showing my design, and these two figures 15 are deemed necessary to properly illustrate my design.

My design relates to configuration, and presents an ornamental and attractive appearance, such as results from the disposition and 20 relation of its parts, and it is to be stamped or otherwise placed on or worked into that part of an incandescent gas-light which is commonly designated the "gallery."

The leading or essential feature of my de- 25 sign may be said to be the ornamental open fretwork spheroid decorated with an open

fretwork fillet which appears to encircle the spheroid.

a is the spheroid, in which appears ornamental fretwork of which the frets are separated by foliated openings *b*, *c*, *d*, *e*, *f*, *g*, *h*, and *i*. Encircling the spheroid appears a fillet *j*, of open fretwork, in which the openings *k* are substantially diamond-shaped.

Obviously my design may be wrought in 35 brass, gold-plate, or any metal or composition of metals and it will be best understood by reference to the accompanying drawings, although it must be borne in mind that the exact shape of the openings *b*, *c*, *d*, *e*, *f*, *g*, *h*, *i*, and *k* is not essential.

What I claim as new, and desire to secure by Letters Patent, is—

The design for a gallery for an incandescent gas-light, substantially as shown and 45 described.

In testimony whereof I have hereunto signed my name.

WILLIAM ELIOT BARROWS.

In presence of—

K. M. GILLIGAN,
F. H. MACMORRIS.
